UNITED STATES PATENT OFFICE

172,826

COMBINED VASE AND LAMP

Irving Davis and Sidney Davis, Philadelphia, Pa.

Application August 20, 1952, Serial No. 21,134

Term of patent 14 years

(Cl. D29—28)

To all whom it may concern:

Be it known that we, Irving Davis and Sidney Davis, citizens of the United States, residing at Philadelphia, in the county of Philadelphia and State of Pennsylvania, have invented a new, original, and ornamental Design for a Combined Vase and Lamp, of which the following is a specification, reference being had to the accompanying drawing forming part thereof:

Fig. 1 is a perspective view of a combined vase and lamp showing our new design;

Fig. 2 is a top plan view thereof;

Fig. 3 is a front elevational view thereof; and

Fig. 4 is a sectional view thereof taken along the line 4—4 of Fig. 3.

We claim:

The ornamental design for a combined vase and lamp, substantially as shown.
